US0D1059627S

(12) **United States Design Patent** (10) **Patent No.:** **US D1,059,627 S**
(45) **Date of Patent:** **** Jan. 28, 2025**

(54) **MEDICAL INSTRUMENT**

(71) Applicant: **Hangzhou Bigfish Bio-tech Co., Ltd.**,
Zhejiang (CN)

(72) Inventors: **Lianyi Xie**, Zhejiang (CN); **Peng Wang**, Zhejiang (CN); **Wenyu Ren**, Zhejiang (CN); **Xiaojuan Xu**, Zhejiang (CN); **Ning Chen**, Zhejiang (CN)

(73) Assignee: **HANGZHOU BIGFISH BIO-TECH CO., LTD.**, Zhejiang (CN)

(**) Term: **15 Years**

(21) Appl. No.: **29/843,171**

(22) Filed: **Jun. 17, 2022**

(51) LOC (15) Cl. **24-02**

(52) U.S. Cl.

USPC **D24/216**; D24/232

(58) **Field of Classification Search**

USPC D24/107, 185, 186, 216, 224, 231, 232, D24/233; D10/81

CPC A61N 1/327; A61N 1/0412; G01N 2035/00306; G01N 2035/00326; G01N 2035/00336; G01N 33/53; G01N 33/5302; G01N 33/569

(57) **CLAIM**

The ornamental design for a medical instrument as shown and described.

DESCRIPTION

FIG. 1 is a top plan view of a medical instrument showing our new design;

FIG. 2 is a bottom plan view thereof;

FIG. 3 is a left side elevational view thereof;

FIG. 4 is a right side elevational view thereof;

FIG. 5 is a front elevational view thereof;

FIG. 6 is a rear elevational view thereof;

FIG. 7 is a front, left, top perspective view thereof;

FIG. 8 is a rear, right, top perspective view thereof; and,

FIG. 9 is a rear, left, bottom perspective view.

In the drawings, the equal-length broken lines depict portions of the medical instrument that form no part of the claimed design.

1 Claim, 9 Drawing Sheets
